UNITED STATES PATENT OFFICE.

ROBERT JARVIS SMOOTHERS, OF HOLYOKE, MASSACHUSETTS, ASSIGNOR TO JAMES T. ROBINSON, OF HOLYOKE, MASSACHUSETTS.

PHOTOGRAPHIC-PRINTING MACHINE.

Application filed November 7, 1925. Serial No. 67,596.

This invention relates to photographic printing machines, more particularly of the step and repeat type, designed primarily for the production of photographic positives and negatives to be employed in connection with the producing of plates for textile and color printing, but it is to be understood that a machine, in accordance with this invention, can be employed for any purposes for which it is found applicable, and the invention has for its objects to provide, in a manner as hereinafter set forth, a machine of the class referred to, for photographically printing a character or design in series or matched relation, or matching portions of the character or design in series, upon a sensitized surface, more particularly a transparent plate, to provide a photographic positive or negative of substantial size for use in the producing of a textile or color printing plate capable of being bent to surround and to be detachably secured to the plate roll or plate cylinder of a printing press.

As is well known in textile or wall paper printing, the plate employed is in the form of a roll or cylinder and to produce the same, the roll, which generally consists of a hollow body, has the periphery thereof engraved or otherwise treated throughout to provide the design which is to be printed on the material. After the printing operation in some instances the roll is smoothed off to enable the engraving on the periphery thereof of a new design and in some instances the roll is discarded and which method entails considerable time, labor, expense and loss. The machine, in accordance with this invention, is designed to produce a photographic positive or negative print of the design, which is to be printed upon the material, upon a transparent base, such as a plate, and such positive or negative is photographed on a flat, bendable, metallic plate. The design on the metallic plate is then etched in a known manner the desired depth, and after the etching of the design the bendable plate can then be detachably secured in cylindrical form to the plate roll or plate cylinder. By the foregoing method the expensive engraving step is dispensed with, as well as the discarding or smoothing off of the printing roll or cylinder, as after the plate has been made in the manner as stated and used, it can be detached from

the roll body or cylinder and the latter again employed in connection with a new plate.

A further object of the invention is to provide, in a manner as hereinafter set forth, a machine of the class referred to, with means for regulating the duration period for the closing of a light circuit to control the service application of the current whereby the period necessary for the application of light rays to a particular photographic plate will be obtained, under such conditions insuring clear, accurate uniform, distinct and perfect photographic prints from the plate upon the sensitized base.

A further object of the invention is to provide, in a manner as hereinafter set forth, a machine of the class referred to, with means to provide for the accurate adjustment of the sensitized base both longitudinally and horizontally to provide for accurate matching of the design or character upon said sensitized base during the step and repeat operation.

Further objects of the invention are to provide, in a manner as hereinafter set forth, a photographic printing machine for the purpose referred to, which is simple in its construction and arrangement, strong, durable, compact, accurate in production, thoroughly efficient in its use, conveniently operated, readily assembled, and comparatively inexpensive to set up.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a side elevation of a photographic printing machine, in accordance with this invention.

Figure 2 is a top plan view thereof.

Figure 3 is a section on line 3-3, Figure 2.

Figure 4 is a section on line 4-4, Figure 3.

Figure 9 is a section on line 9—9; Figure 10.

Figures 10 to 14, both inclusive, are detail views of the escapement mechanism for the carrier.

Figure 15 is a fragmentary view, in side elevation, of one of the spring controlled shifting arms for the lamp house.

Figure 16 is a fragmentary view, in section, of an operating means for the carrier escapement mechanism.

Figures 17 to 20, both inclusive, are details of the operating means for the carrier escapement mechanism.

Figures 21 to 23, both inclusive, are detail views illustrating elements for the carrier escapement mechanism.

Figure 24 is a detail of an element of the plate holder.

Figure 25 is an elevation of the circuit opening and closing device for the lighting circuit.

Figure 26 is a section on line 26—26; Figure 25.

The machine comprises a housing of substantial weight to prevent accidental shifting thereof, as well as to prevent any movement of the housing during the operation of the machine. The housing is referred to generally by the reference character 1, is of greater height at its rear than at its front, and open at its front, rear and bottom. The bottom or base of the housing is formed from a rectangular frame 2 of metallic material of the desired weight, and the sides of the housing are formed from a pair of vertically disposed metallic plates 3, 4 of like construction, and each of which is positioned to be flush with an end edge of the frame 2, as well as flush with the front and rear edges of said frame 2. The forward edge 5 of each side plate is of materially less height than the rear edge 6 thereof. The top edge of each side plate consists of an upwardly extending and rearwardly inclined portion 7 and a downwardly and rearwardly extending inclined portion 8 of materially less length than the portion 7. The portion 7 extends from the top of the front edge 5 and terminates in the upper end of the portion 8. The portion 8 extends from the top end of the portion 7 and terminates in the upper end of the rear edge 6. The inner face of the side plate 3, as well as the side plate 4 is formed with a pair of inwardly extending, spaced lugs 9, at the bottom thereof and which seat upon

an end of the frame 2 and are fixedly secured therewith by the hold-fast devices 10. Extending inwardly from the portion 7 of the top edge of each side plate is a flange 11, upon which seats the top 12 of the housing, and the latter is secured to the flanges 11 by the hold-fast devices 13. The top 12 extends upwardly and rearwardly at an inclination and is formed with a central opening 14 for a purpose to be presently referred to. The top 12 is furthermore provided with a pair of spaced, transversely extending slots 15, 16, in the upper portion thereof, and each is positioned between the opening 14 and one side of the top. The function of the slots 15, 16 will be presently referred to.

Secured to the top 12 and each side wall of the housing 1, is an angle-shaped member 17, which is positioned against the side and overlaps the top of the housing 1, and the hold-fast devices for securing the angle-shaped member 17 in position are indicated at 18. The angle-shaped members are secured centrally of the sides of the top 12 and each of which is formed with a pair of spaced arms 19 formed with guideways 20. The arms 19 at their upper ends are secured together by a cross plate 21, to which is secured an end piece 22 of a cross head 23 formed centrally with an integral rectangular frame 24. The cross head 23 is reinforced by lengthwise disposed ribs 25, and each of which extends from an end piece 22 and terminates in the frame 24. The members 17, arms 19 and cross head 23 provide a guide structure common to the lamp house and the shifting means therefor to be presently referred to. The guide structure is disposed at an inclination, or in other words at an obtuse angle with respect to the vertical median of the housing, and the lamp house is also disposed at the same angle.

The lamp house operates through the frame of 24 of the cross head 23 and the holder carried thereby for the plate provided with the design to be printed operates through the opening 14 in the head 12 of the housing. The lamp house consists of a body portion 26 formed with a circular enlargement 27 intermediate its ends and a laterally extending flange 28 at the top of the enlargement 27. The lower end of the body portion 26 is offset, as at 29, see Figure 4, and which extends into the rabbeted upper end 30 of the holder or carrier 31 for the printing plate 32. The holder 31 is clamped tightly against the lower end of the body portion 26 by a plurality of clamping devices 33 and each of which consists of a short bar 34, pivoted at its lower end, as at 35, to the carrier 31 and having its upper end peripherally threaded. The body portion 26 is formed with laterally extending

pairs of lugs 36, each of which coacts with a bar 34. Carried on the upper end of each bar 34 is a clamping nut 37. When the carrier 31, with its plate 32 positioned therein, is arranged at the inner end of the lamp house, the rods 34 are swung upwardly to extend into the pairs of lugs, after which the clamping nuts 37 are screwed home against the pairs of lugs and by this arrangement the carrier 31 is tightly clamped against the lower end of the body 26, whereby on the shifting of the lamp house the carrier 31 will be carried therewith. Furthermore, this arrangement provides for removably clamping the printing plate carrier 31 to the lamp house.

A light excluding means is provided for the opening 14 and the said means consists of a frame 38 which surrounds and is spaced from the opening 14 and is furthermore secured to the top 12 by hold-fast devices 39. Extending under the outer portion of the frame 38 is the lower end of a flexible member 40, which surrounds that part of the body portion 26 below the enlargements 27, and furthermore surrounds the printing plate carrier 31. The upper end of the flexible member 40 is secured between a flange 41 and the enlargement 27. The flange 41 is integral with the body portion 26 and is spaced from the enlargement 27.

The top of the lamp house is indicated at 42 and is detachably secured to the body portion 26 in any suitable manner. The top 42 carries a socket 43 for a lamp 44, which is suspended within the body portion 26 and spaced from the printing plate 32. The top 42 of the lamp house, see Figure 2, is provided with an opening 45 for the passage of the circuit wires to the lamp 44, and said top 42 is furthermore provided with an opening in which is secured a transparent member 46, preferably red in color, for the purpose of viewing the interior of the chamber 47 formed by the lamp house and in which is suspended the lamp 44.

The shifting mechanism for the lamp house is spring controlled and manually operated and when operated the actuation thereof is had against the action of the controlling springs therefor. The said lamp house shifting mechanism comprises a split clamping collar 48 formed with a pair of opposed lugs 49. The collar 48 is positioned to surround the offset portion 27 and to abut against the flange 28. The collar 48 is tightly clamped against the offset portion 27 by a clamping screw 50, which has threaded engagement with the lugs 49 and further has means, as at 51, to facilitate the turning thereof to clamp or release the collar 48 with respect to the enlargement 27. Formed integral with the collar 48, at diametrically opposite points, is a pair of oppositely dis-

posed split socket forming members 52, each provided at the outer end with a pair of depending lugs 53, having threadedly engaging therewith a binding screw 54 for fixedly securing one end of a coupling rod 55 to the 70 socket forming member.

Slidably mounted in the grooves 20 of each pair of arms 19 is a block 56, having an inwardly extending socket forming member 57 for the reception of the outer end of 75 a coupling rod 55. Extending from the outer face of each block 56, and of a length to project beyond a side of the housing 1, is an apertured lug. The apertured lug of one block 56 is indicated at 58, and that of 80 the other block 56 at 59.

Pivotedly connected to the lugs 58, 59 are the depending yokes 60, 61 and secured to the yokes 60, 61 as well as depending therefrom are the shifting rods 62, 63 and each of these latter extends through a guide 64 secured to the outer face of a side wall of the housing. The blocks 56 and rods 62, 63 are disposed at the same inclination as the lamp house. The lower end of the shifting rod 62 is pivotally connected, as at 65, to the upper end of an inclined operating lever 66 therefor. The lever 66 is pivotally connected, intermediate its ends, as at 67, to the side 3 of the housing, and the lower or forward end of the lever 66 is pivotally and adjustably connected, as at 68, to the lower end of a shifting link 69 therefor. The upper end of the link 69 is pivotally connected, as at 70, to the inner end of an operating lever 71, which is pivotally connected at a point between its transverse median and its rear end upon a pivot 72. The operating lever 71 projects forwardly from the side 3 of the housing 1 and is provided with a handle 73. Secured to the side wall 3 of the housing 1 is a keeper 74 for the lever 71, and which also constitutes a stop for the upward movement of the lever. Secured to the side wall 3 of the housing 1 and arranged in the path of the outer portion of the lever 71, when the latter moves downwardly, is an adjustable stop 75.

The shifting rod 63, see Figure 15, has its lower end pivoted, as at 76, to the upper end of an inclined link 77, the latter being pivoted, as at 78, to the side wall 4 of the housing 1.

Adjustably mounted on the rod 62, as well as the rod 63, is a stop collar 79, and mounted on said rods and interposed between the collar 79 and the guide 64 are the coiled controlling springs 80 for the lamp house shifting mechanism.

Arranged within the housing 1 and shiftable transversely thereof is a carrier referred to generally by the reference character 81 and which supports the holder for the sensitized base, which is to be printed upon. The carrier 81 is spring controlled, is nor-

mally locked and intermittently released through the medium of an escapement mechanism and has its movement intermittently arrested. The intermittent transverse movement of the carrier 81 positions portions of the sensitized base to be successively printed thereon, or in other words provides for the step and repeat operation so that the prints will be successively made and matched in a row-like manner upon the sensitized base, which preferably is a sensitized glass plate; although it is to be understood that the sensitized base, which is referred to by the reference character 82, can be set up of any desired material. The carrier 81 travels and is supported on a pair of track members 83, 84, of cylindrical cross section, and which are secured to the side members 3 and 4 of the housing. The track member 83 is arranged above the track member 84 and positioned at the rear of the housing 1, and the track member 84 is positioned in proximity to the bottom of the housing and forwardly with respect to the transverse median thereof. The carrier 81 consists of a pair of inclined side members 85, 86, each formed with an inverted V-shaped top edge 87 and an upper, an intermediate and a lower projection 88, 89 and 90 at the lower edge. The side members 85 and 86 are connected together, see Figure 6, by a pair of bottom members referred to generally by the reference characters 91 and 92 and each of which is formed with an upper and a lower portion 93, 94 disposed at an angle with respect to each other. The upper portion 93 of the bottom member 91 is secured to the projections 88 by the hold fast devices 95. The upper portion 93 of the member 92 is secured to the projections 90 by the hold-fast devices 96. The portion 95 of the bottom members extends at the same inclination as the inclination of the side members 85, 86 of the carrier and the portions 94 of the bottom members are vertically disposed and are arranged in proximity to the track members 83, 84. The portion 94 of each of the bottom members 91 carries a pair of shafts 97 provided with guide rollers 98. The guide rollers 98 of the bottom member 91 travel on the track member 83, and the guide rollers 98 of the bottom member 92 travel on the track member 84. Secured to the side member 86 is a flexible pulling member 99, which travels over a guide pulley 100 and is connected, as at 101 to a controlling spring 102 which winds within a housing 103 secured to the inner face of the side member 4 of the housing 1. The function of the spring 102 is to normally act to shift the carrier 81 in a direction towards the side member 4 of the housing 1. See Figure 4. For shifting the carrier 81 towards the side wall 3 of the housing 1, a manually operated device is provided and which consists of a shaft 104 extending lengthwise of the housing in proximity to the side member 3 thereof and which is journaled in bearings 105 secured to the frame 2. The shaft 104 projects forwardly from the housing, see Figure 6, and carries an operating handle 106 therefor. The inner end of the shaft 104 carries an elongated crank arm 107 to the upper end of which is pivoted, as at 108, a link 109, and the latter is pivoted, as at 110, to a lug 111, which projects from the side member 85 of the carrier 81. Associated with the carrier 81 is a combined stop and escapement mechanism and which is released to allow the carrier to shift a predetermined distance on the return of the operating lever 71 to normal position. The said combined stop and escapement mechanism for the carrier 81 comprises a rock shaft 112 journaled at one end in a bearing 113, which is secured to the inner face of the side member 4 of the housing 1. The rock shaft 112 extends through a bearing 114 secured to the inner face of the side member 3 of the housing, extends outwardly from said member 3, see Figure 16, and carries on its projecting end an adjustable collar 115 provided with a set screw 116. The collar 115 moves with the shaft 112 and mounted on the latter, as well as abutting against and connected with the collar 115, as at 117, is a notched disk 118. The notch in the edge of the disk 118 is indicated at 119. See Figure 19. The connecting means between the collar 115 and the disk 118 consists of a pin carried by the collar 115 and extending through an oval-shaped slot 120 in the disk 118. Loosely mounted on the shaft 112, exteriorly of the disk 118, is one end of a lever 121 which has its other end pivotally connected, as at 122, see Figure 1, to the upper end of a shifting link 123 therefor. The link 123 is pivotally connected, as at 124, to the operating lever 71. The lever 121 carries a pivoted dog 125, engaging in the notch 119 for the purpose of shifting the disk 118, thereby rocking the shaft 112 for a purpose to be presently referred to. After the disk 118 has been shifted to rock the shaft 112, it is locked in such position and the locking means therefor comprises a rod 126 pivotally connected at its inner end, as at 127, to the disk 118. The rod 126 extends through a guide 128 secured to the outer face of the side member 2 of the housing 1. The rod 126 extends forwardly from the front of the housing and carries a handle member 129. Secured to the outer face of the side member 3 of the housing is a stop lug 130 having a bevelled top and against which rides a bevelled locking lug which depends from the rod 126. When the disk 118 is shifted by the

dog 125, the rod 126 is carried with the disk 118 and the movement of the rod 126 is such that the lug 131 will ride over the lug 130 and engage the rear face of the lug 130, thereby locking the disk 118 in the position to which it had been shifted. When the operator moves the lever 71 downwardly to make the print, or for the purpose of shifting the lamp house inwardly, the link 123 is carried therewith and before the operator shifts the lever 71, the rod 126 is released from the lug 130 and positioned so that the lug 131 will be forwardly of or on the lug 130. When the rod 126 is moved to such position, the disk 118 is shifted therewith, due to the slot 120 which is of oval contour and when the disk 118 is so shifted, the notch 119 thereof is positioned in the path of the dog 125. The function of shifting the disk 118 by the rod 126 will be set forth in connection with the stop and escapement mechanism for the carrier.

The shaft 112 centrally thereof, carries a primary stop element A comprising a rectangular body portion 131 formed with an eccentrically disposed opening 132 and an oval-shaped slot 133 disposed upon an arc. Projecting from one side of the body portion 131 at the top thereof is a stop lug 134 having a bevelled lower side 135. The lug 134 projects towards the front of the housing. The body portion 131 is loosely mounted on the shaft 112 and at each side is formed with a boss 136. Fixed to the shaft 112, at one side of the stop element A is a stop element B, which comprises a disk 137 formed with an opening 138 for mounting on the shaft 112. The disk 137 is formed with a radially disposed bore 139 which extends from one edge of the disk 137 and terminates at the opening 138. The wall of the bore 139 is threaded for the reception of a locking pin 140 to secure the disk to the shaft 112. The disk 137 has one side formed with a laterally extending pin 141 which operates in the slot 133 for the purpose of carrying the stop element A with the stop element B in both directions therewith, but said slot 133 provides for lost motion at the start of the stop element B when moving in either direction. Formed integral with the disk 137 and projecting towards the front of the housing 1 is a substantially elongated stop member 142 having a portion of one side bevelled, as at 143. Mounted on the shaft 112 and abutting against one of the bosses of the stop element A is a collar 144 secured to the shaft by a locking pin 145. The stop element B, in connection with the collar 144, prevents lengthwise shifting of the stop element A with respect to the shaft 112. The locking pins 140 and 145 permit of the adjustable positioning of the stop elements A and B and collar 144 on the shaft 112.

Secured to each of the projections 89 is a hanger referred to generally by the reference character 146, and best shown in Figure 21. Each of the hangers comprises an apertured head 147 through which extend hold-fast devices 148 for fixedly securing the head to a projection 89. Each of the hangers further includes a depending arm 149, which is disposed at an inclination and formed with a V-shaped seat 150 for the reception of one end of a stationary shaft 151, which has adjustably mounted thereon a series of limiting members 152 which act in connection with the stop elements A and B to limit the transverse shifting movement of the carrier by the pulling spring 102 in connection with the pulling member 99. The shaft 151, best shown in Figure 23, is formed with reduced polygonal-shaped ends 153 and a cylindrical intermediate portion 154. The shaft 151 is provided lengthwise thereof with a V-shaped groove 155. The ends 153 of the shaft 151 can be secured upon their seats 150, in a manner to prevent lengthwise shifting of the shaft relative to the hangers 146. Each of the limit members 152, best shown in Figures 3 and 8, consists of a collar 155' provided with a pair of right angularly disposed bevelled limit lugs 156, 157. The lug 156 coacts with the stop member 142 and the lug 157 coacts with the stop lug 134 and which action will be hereinafter more specifically referred to.

The inner diameter of each of the limit members 152 is greater than the diameter of the shaft 151 and arranged in each of said limit members 152 as well as bearing against one side thereof is a holding member, best shown in Figures 8 and 22, and which comprises a V-shaped body portion 158 having extended outwardly from one end thereof a shank 159. The body portion 158 seats in the groove 155 of the shaft 151 and is clamped against the wall thereof by a clamping screw 160, which has threaded engagement with the limit member 152 and bears against the flat face of the body portion 158. See Figure 8, and which in connection with the holder member, fixedly secured the limit member in adjusted or set position on the shaft 151.

It will be assumed that the position of the stop and escapement mechanism is as shown in Figures 3 and 8 and in such position the lugs 156, 157 are in engagement with the stop member 142 and lug 134 respectively and which retains the carrier from shifting in a transverse direction against the action of its spring controlled pulling means. Now it will be assumed that the shaft 112 has been rocked due to the action of the dog engaging with the disk 118, as the shaft is shifted in a direction to lower the stop member 142 the lug 156 is cleared and the carrier will then be shifted in a direction towards

- the wall 4 of the housing. The lug 157 riding against the bevelled face of the lug 134 will clear the same, due to the lost motion provided by the slot 133. At the time 5 the lug 157 clears the lug 134, the pin 141 of the stop element B will then act to carry the stop element A bodily therewith and which will position the lug 134 in the path of the lug 157 of the advancing limit member 152.
- 10 The carrier will then be arrested. The rod 126 is then pulled outwardly which shifts the stop member 142 in the path of the lug 156 of the limit member which has been arrested by the lug 157 thereof abutting 15 against the lug 134. The slot 133 in the stop element A provides for lost motion to the effect that the stop element A is not shifted by the stop element B until after the stop member 142 is positioned in the path of the lug 156. The stop and escapement mechanism provides for the intermittent shift of the carrier a predetermined distance so as to carry out the operation of the step and repeat.
- 20 Shiftably mounted on the carrier 81 is a plate holder employed for carrying or holding the sensitized surface which is to be photographically printed upon and as before indicated said sensitized surface, which will be hereinafter referred to as a transfer plate, 25 is indicated by the reference character 82. The plate holder is referred to generally by the reference character 161, is of rectangular contour and comprises a bottom 162, a pair 30 of end walls 163, 164, a top wall 165 and a bottom wall 166. The top wall 165 is slotted, 35 as at 167, for the passage of a closure slide 168 for the holder. Secured to each of the walls of the holder is a strip 169 provided 40 with a compressible light excluding means 170, which rides against the inner face of the top 12 of the housing. Each of the side walls of the plate holder is formed with an inverted V-shaped groove 171 for the reception 45 of the inverted V-shaped upper edge of the side members 85, 86 of the carrier.
- The plate holder 161 is provided with a manually operated combined stop and escapement mechanism for permitting shifting 50 of the plate holder in a direction at right angles to the direction in which the carrier 81 is shifted. The plate holder normally tends to shift downwardly on the carrier by gravity and one of the side members of the 55 carrier, that is side member 86, has its lower portion provided with a stop 172 for arresting the plate holder when shifted to its lowermost position as well as supporting the plate holder in such position.
- 60 Associated with the lamp house is a gage to align the printing plate 32 so that it will be perfectly straight or parallel with the machine or the transfer plate, thus assuring the joining or matching of a continuous design. The gage comprises a pair of gradu-
- ated bars 173 secured by hold-fast devices 174 upon the upper face of the top 12 of the housing 1, and one bar is arranged in proximity to the slot 15 and the other to the slot 16. Operating upon and overlapping said graduated bars is a pair of setting members 175, which are connected by a straight cross head 176. Each setting member is provided with a set screw 178. The operation of the gage is such that when a new printing plate 70 is to be placed in the light house 26, the flexible member 40 is removed from the ring 38 and new plate 32 inserted in its holder. The set screws 178 are loosened and the cross head or bar 176 is brought down between 75 ring 38 and plate 32. The top of the light house 26 is removed and artificial light is placed underneath the light house, thus making it possible to look into the top of the light house 26 and see when the plate 32 80 is perfectly straight. If plate 32 is not perfectly straight, clamp 51 is then loosened allowing light house 26 to be turned either to right or left, thus bringing plate 32 into perfect alignment with cross head or bar 176. 85 This assures getting all the repeat straight on the first print, as without the employment of the gage it would be necessary to print several times before getting the proper alignment.
- 90 The stop and escapement mechanism for the plate holder is of the same construction as the stop and escapement mechanism referred to in connection with the carrier with this exception that the stop and escapement mechanism for the plate holder is manually operated. The shaft 184 of the stop and escapement mechanism for the plate holder, and which corresponds to the shaft 112 of the stop and escapement mechanism for the carrier, is mounted in a pair of bearings 185, 95 secured to the upper portions 93 of the bottom members 91 and 92 of the carrier. The shaft 184 extends from one of the bearings 185 and is provided with a handle 186 for the purpose of manually operating the same.
- 100 The shaft 187 of the stop and escapement mechanism for the plate holder, which corresponds to the shaft 151 of the stop and escapement mechanism for the carrier, is mounted in a pair of hanger members referred to generally by the reference character 188, and which consists of an apertured head piece 189 secured to the bottom 162 of the plate holder by the hold-fast devices 190 and further includes a depending arm 191 provided with a V-shaped seat 192 for an 105 end of the shaft 184. Otherwise than that as stated the construction of the stop and escapement mechanism for the plate holder is 110 the same as that set forth in connection with the stop and escapement mechanism for the carrier. The stop and escapement mechanism for the plate holder can be operated 115 from the open front of the housing 1.

- 130

The circuit opening and closing device for regulating the duration period for the closing of the lighting circuit to control service application of the current whereby the period necessary for the application of light rays to a particular photographic plate will be obtained to insure clear, accurate, uniform, distinct and perfect photographic prints from the printing plate upon the transfer plate, can be of any suitable construction, preferably as that disclosed in Figures 25 and 26 and as fully set forth in my application filed September 11, 1925, serially numbered 55,807. The circuit opening and closing device is operated from one of the blocks 56 of the operating mechanism for the lamp house and the mechanism which is actuated to open and close the circuit is secured to one of the arms 19 which associates with that sliding block 56 which carries the actuating means for the device. The position of the circuit opening and closing device is clearly shown in Figure 2.

The circuit opening and closing device comprises a stationary housing 193 provided in one of the walls thereof with a lengthwise slot 194. Connected to the block 56 so as to move therewith is a plate 195 provided with an interiorly threaded sleeve 196 with which threadedly engages a shifting member 197. The member 197 can be adjusted with respect to the sleeve 196 and after adjustment detachably secured in such position by a retaining screw 198. The circuit wire connections leading from the source of supply to the circuit opening and closing device and from there to the lamp 44 are indicated at 199. One of the circuit wires is indicated at 200 and the other at 201. The bottom of the housing 193 is provided with a slot 202. Another of the walls of the housing 193 at its lower end is provided with a slot 203. Arranged within the housing 193 is a plate 204 of insulation. Secured to the plate 204 is a pair of strips of insulation 205 and against the upper portion thereof is secured a plate 206 of insulation. Secured to the lower end of the strips 205 are small blocks 207, 208 of insulation. Slidably adjustable between the strips 205 is a vertically movable carrier 209 of insulation and which has embedded in one face thereof a tapered contact member 210, of the same length as the length of the carrier 209 and which gradually increases in width from the bottom edge to the top edge of the carrier 209. The retaining blocks 207, 208 overlap the carrier 209. The carrier 209 is vertically adjusted and maintained in its adjusted position and the means therefor is as disclosed in my application aforesaid and it is thought unnecessary to specifically describe and show the same. The circuit wire 201 is electrically connected to the contact 210. The circuit wire 200 is electrically connected to a conducting arm 64', which is secured at one end to the upper portion of the plate 206 and has its other end bent inwardly or inturned upon itself as at 65' for the purpose of forming a contact abutment. Secured to the plate 206, below the arm 64' is a pair of spaced stop pins 66', 67'. Pivotally connected to the plate 206, as at 68', and below the pins 66', 67' is an oscillatory conductor member which normally contacts with the abutment formed by the inturned end of the arm 64' and said conductor member is formed of an inverted yoke-shaped lower portion 69' having an upwardly extending arm 70' formed integral therewith. The arm 70' extends between the pins 66' and 67' and below the inner face of the arm 64'. The lower portion 69' of the conductor member depends below the plate 206 and the arms of said member are indicated at 69'' and 70''. The said arms are arranged in the path of the circuit opening and closing element of a spring controlled oscillatory circuit opening and closing mechanism which is arranged below the plate 206 and is engaged by a spring controlled latching member 211 which extends through the slot 203 and is positioned in the path of the actuating member 197. The said oscillatory circuit opening and closing mechanism not only coacts with the said conductor member, but also with the contact 210.

The oscillatory circuit opening and closing mechanism is shifted to close the circuit through the medium of a controlling spring therefor and returned to inactive position, or positioned to open the circuit, also by a controlling spring. The controlling springs will be presently referred to. The oscillatory circuit opening and closing mechanism also includes a governor to provide for its operation at uniform speeds when released to close the circuit and shifted to inactive position to open the circuit.

The spring controlled oscillatory circuit opening and closing member includes a headed pivot 71' upon which is pivoted a bell crank member having its arms indicated at 72', and 72'' and connected to the arm 72' is a toothed quadrant 73'. Extending from the arm 70' to the arm 72' is a circuit conductor 74' whereby said arms are electrically connected together. The arm 72' carries an arcuate bar 75' formed with a seat 76' engaged by the latch 211; the latter being spring controlled, as at 211'. The controlling spring for the bell crank lever is indicated at 77'. The quadrant 73' is employed for actuating the governor 79' positioned in the path of the double-armed lever 80'. One of the arms of the lever 80' is indicated at 81' and which coacts with the lug 79'.

The other arm of the lever 80' is indicated at 82' and which coacts with a return spring 83' fixed to a part of the machine body.

Secured to the arm 72' of the bell crank 5 and of less length than the length of said arm is a bar 85'.

The elements of the circuit opening and closing device are briefly referred to but for a more detailed and specific description of 10 the elements of the device reference is had to the applicant's co-pending application aforesaid.

The bar 85' acts as a means to oscillate the conductor member so that the arm 70' thereof will be moved into and out of engagement with the inturned portion 65' of the arm 64' and as before stated the inturned portion 65' constitutes an abutment contact. Normally the arm 70' of the conductor member is in engagement with the abutment contact and which is caused by the bar 85' engaging in the arm 69'' of the conductor member so that the latter will be rocked or shifted to the position shown in 25 Figure 26. When the bar 85' moves in a clockwise direction, that is to say away from the arm 69'', the arm 72' of the bell crank which is termed a wiper member will engage with the contact 210 and the circuit 30 will be maintained closed as long as the wiper member is in engagement with the contact member 210. As the wiper member, arms 72', moves with the bar 85' in a clockwise direction said bar 85' will engage the arm 70'' 35 of the conductor member and shift the arm 70' of the conductor member out of contact with the inturned end 65' of the member 64'. When the bar 85' engages the arm 70'' the conductor member will be shifted to a position opposite to that shown in Figure 26 40 and the arm 70' thereof will engage the pin 66'. At this time the bar 85' will be moved in a counterclockwise direction and towards the arm 69'' and during such movement 45 of the bar 85' the wiper member, arm 72', will engage the contact 210, but as the arm 70' is out of engagement with the inturned portion 65' of the arm 64' the circuit will not be closed. As the bar 85' moves towards 50 the arm 69'' it will abut the latter and at the time of the abutment the latch 211 will engage the seat 76' and maintain the parts in the position shown in Figure 2. The shifting of the bell crank formed by the arms 72' 55 and 72'' is caused by the spring 77', when the latch member 211 is shifted from engagement with its seat 76', and the actuation of said bell crank is had against the action of the spring 83' which is placed under tension through the medium of the lever 80'. The spring 77' provides for moving the arm 72' in a direction towards and over the contact 210, and the spring 83' acts as a means 60 for moving the bell crank lever in an oppo-

site direction under such conditions that an 65 oscillatory movement is given to the wiper member which is arm 72' of the bell crank. When the bell crank lever is shifted by the spring 83', the bar 75' rides against the nose of the latch member 211 until said latch 70 member engages seat 76' which maintains parts in the position shown in Figure 26. The adjusting of the contact 210 to increase or decrease the width thereof engaged by the wiper member 72' controls the service application 75 of the current for the period necessary for the application of light rays to a particular photographic plate.

The combined stop and escapement mechanism for the spring controlled carrier permits of the latter shifting transversely the desired extent when successively printing the design or matched portions thereof in a row on the transfer plate 82 and such mechanism is actuated to release the carrier when the shifting mechanism for the lamp house is moved upwardly through the medium of the controlling springs therefor.

The combined stop and escapement mechanism for the gravity movable transfer plate holder permits when such mechanism is manually actuated the shifting of such plate holder downwardly the desired distance to position another portion of the transfer plate 82 so that such portion can be printed with another row of designs or matched portions of the designs and with the lower row matching with the upper row.

The limit members of each escapement mechanism can be adjusted on their respective shaft so that the desired shift of the carrier or transfer plate holder can be obtained for the purpose of matching the prints. The bevelling of the stop lugs and stop members of the escapement mechanisms will permit of the carrier or the transfer plate holder to be shifted to initial position.

The carrier is shifted to initial position on the actuation of the rock shaft 104 by the handle member 106. The transfer plate holder is shifted to initial position manually or any suitable means can be employed for such purpose.

The construction of the elements 104, 106, 107, 109 and 111, which form the means for shifting the carrier to initial position, is such as not to interfere with the shifting of the carrier from initial position.

It is thought that the operation of the machine is clearly understood in view of the specific operation as set forth in connection with the several mechanisms thereof, but it will be stated that on the depression of the lever 71 the lamp house carrying the printing plate 32 will be shifted until said plate engages the transfer plate 82 and at which time the lighting circuit will be closed, under such conditions printing the design or a

matched portion thereof on the plate 82. The circuit opening and closing device provides for controlling the service application of the current to obtain the period necessary for the application of light rays to a particular printing plate. On a release of the lever 71 the shifting mechanism for the lamp house will return to initial position, and on the return will actuate the stop and escapement mechanism for the carrier 81 to permit of the latter to be shifted the desired extent so as to position another portion of the plate 82 to be printed. As before stated, the shifting of the transfer plate holder is had on the manual operation of the stop and escapement mechanism therefor.

It is thought the many advantages of a photographic printing machine of the step and repeat type, in accordance with this invention, can be readily understood, and although the preferred embodiment of the invention is as illustrated and described, yet it is to be understood that changes in the details of construction can be had which will fall within the scope of the invention as claimed.

What I claim is:

1. A photographic printing machine comprising a carrier, a gravity movable sensitized body holder mounted on the carrier, means for shifting said carrier in one direction to position portions of the sensitized body on the holder to be successively photographically printed, a stop and escapement mechanism coacting with said carrier to provide for the intermittent shifting thereof a predetermined distance, means for photographically printing on said body after each shift of the carrier, and a stop and escapement mechanism associated with said holder to provide for the intermittent shifting thereof in a direction at right angles to the shift of the carrier.

2. A photographic printing machine comprising a carrier, a gravity movable sensitized body holder mounted on the carrier, means for shifting said carrier in one direction to position portions of the sensitized body on the holder to be successively photographically printed, a stop and escapement mechanism coacting with said carrier to provide for the intermittent shifting thereof a predetermined distance, means for photographically printing on said body after each shift of the carrier, a stop and escapement mechanism associated with said holder to provide for the intermittent shifting thereof in a direction at right angles to the shift of the carrier, and means connected to said carrier for shifting it to its initial position.

3. A photographic printing machine comprising a carrier, a gravity movable sensitized body holder mounted on the carrier, means for shifting said carrier in one direction to position portions of the sensitized

body on the holder to be successively photographically printed, a stop and escapement mechanism coacting with said carrier to provide for the intermittent shifting thereof a predetermined distance, means for photographically printing on said body after each shift of the carrier, and means for photographically printing on said body after each shift of the carrier and including a light source and means for adjustably controlling the duration of the illuminating period of said light source.

4. A photographic printing machine comprising means for shifting in one direction a sensitized body to position portions thereof to be photographically printed, a carrier for said means, means for intermittently releasing said carrier to permit of the latter shifting a predetermined distance in a direction at right angles to the direction in which said body was shifted to provide for aligning successive photographic prints in row-like form on said body, and means shiftable towards said carrier for photographically printing said body after each shift of the carrier and including a light source and adjustable means for controlling the activity of said source.

5. A photographic printing machine comprising a normally retained, gravity movable holder for a sensitized body, a carrier for said holder, a stop and escapement mechanism coacting with said holder and adapted when actuated to permit of the holder shifting lengthwise a predetermined distance on the carrier to position portions of said body to be photographically printed, means for shifting said carrier, a stop and escapement mechanism coacting with said carrier to provide for the intermittent shifting of the latter a predetermined distance in a direction at right angles to the direction in which said holder was shifted to provide for aligning successive photographic prints in row-like form on the sensitized body carried by the holder, and means for photographically printing on said body after each shift of the carrier and including a light source and adjustable means for controlling the activity of the carrier.

6. A photographic printing machine comprising a normally retained, gravity movable holder for a sensitized body, a carrier for said holder, a stop and escapement mechanism coacting with said holder and adapted when actuated to permit of the holder shifting lengthwise a predetermined distance on the carrier to position portions of said body to be photographically printed, means for shifting said carrier, a stop and escapement mechanism coacting with said carrier to provide for the intermittent shifting of the latter a predetermined distance in a direction at right angles to the direction in which said holder was shifted to

- provide for aligning successive photographic prints in row-like form on the sensitized body carried by the holder, means for photographically printing on said body 5 after each shift of the carrier and including a light source and adjustable means for controlling the activity of the carrier, and an actuating means for the stop and escapement mechanism for the carrier, said actuating means operated from the means for photographically printing on said body.
7. A photographic printing machine comprising a normally retained, gravity movable holder for a sensitized body, a carrier for said holder, a stop and escapement mechanism coacting with said holder and adapted when actuated to permit of the holder shifting lengthwise a predetermined distance on the carrier to position portions 10 of said body to be photographically printed, means for shifting said carrier, a stop and escapement mechanism coacting with said carrier to provide for the intermittent shifting of the latter a predetermined distance in a direction at right angles to the direction in which said holder was shifted to provide for aligning successive photographic prints in row-like form on the sensitized body carried by the holder, means 15 for photographically printing on said body after each shift of the carrier and including a light source and adjustable means for controlling the activity of the carrier, and means operated forwardly of the carrier 20 for returning the latter to initial position.
8. A photographic printing machine comprising a normally retained, gravity movable holder for a sensitized body, a carrier for said holder, a stop and escapement mechanism coacting with said holder and adapted when actuated to permit of the holder shifting lengthwise a predetermined distance on the carrier to position portions 25 of said body to be photographically printed, means for shifting said carrier, a stop and escapement mechanism coacting with said carrier to provide for the intermittent shifting of the latter a predetermined distance in a direction at right angles to the direction in which said holder was shifted to provide for aligning successive photographic prints in row-like form on the sensitized body carried by the holder, means for photographically printing on said body after each shift of the carrier and including a light source and adjustable means for controlling the activity of the carrier, and means operated forwardly of the carrier 30 for returning the latter to initial position.
9. A photographic printing machine comprising a holder for a sensitized body, a carrier for said holder, a stop and escapement mechanism supported from the holder and the carrier and providing means to permit of the holder shifting by gravity a predetermined distance lengthwise of the carrier to position portions of said body to be photographically printed, means for shifting said carrier, a stop and escapement mechanism coacting with said carrier to 35 permit of the intermittent shifting of the latter a predetermined distance in a direction at right angles to the direction in which said holder was shifted to provide for aligning successive photographic prints in row-like form on the sensitized body in the holder, means shiftable towards said carrier for photographically printing on said body after each shift of the carrier and including a light source and means for varying the period of activity of said source, and an actuating means for the stop and escapement mechanism for the carrier, said actuating means operated from the means for photographically printing on said body, and means operated forwardly of the carrier for returning the latter to initial position.
10. A photographic printing machine comprising a holder for a sensitized body, a carrier for said holder, a stop and escapement mechanism coacting with said holder to permit of the latter shifting a predetermined distance by gravity to position portions of said body to be photographically printed, means for shifting said carrier, a stop and escapement mechanism coacting with said carrier to permit of the shifting of the latter a predetermined distance in a direction at right angles to the direction in which said holder was shifted to provide for aligning successive photographic prints in row-like form on the sensitized body in the holder, and means shiftable towards said carrier for photographically printing on said body after each shift of the carrier and including a light source and means for varying the period of activity of said source.
11. A photographic printing machine comprising a gravity shiftable holder for a sensitized body, a normally locked releasable carrier for said holder, a stop and escapement mechanism supported from the holder and the carrier and providing means to permit of the holder shifting by gravity a predetermined distance lengthwise of the carrier to position portions of said body to be photographically printed, means for shifting said carrier, a stop and escapement mechanism coacting with said carrier to 45 permit of the intermittent shifting of the latter a predetermined distance in a direction at right angles to the direction in which said holder was shifted to provide for aligning successive photographic prints in row-like form on the sensitized body in the holder, means shiftable towards said carrier for photographically printing on said body after each shift of the carrier and including a light source and means for varying the period of activity of said source, and an actuating means for the stop and escapement mechanism for the carrier, said actuating means operated from the means for photographically printing on said body, and means operated forwardly of the carrier for returning the latter to initial position.

extensible and contractile light excluding element associated with said means for photographically printing.

12. In a photographic printing machine 5 a lamp house provided with means for suspending a lamp therein, a printing plate carrier abutting against the lower end of the lamp house, said carrier provided with pivoted elements and said lamp-house having fixed means coacting with said elements for detachably clamping the carrier against the lower edge of the lamp house, and said lamp house further provided with a colored transparent means for viewing the interior of the lamp house.

13. In a photographic printing machine a lamp house provided with means for suspending a lamp therein, a printing plate carrier abutting against the lower end of the lamp house, said carrier and lamp house having coacting means thereon for detachably clamping the carrier against the lower edge of the lamp house, the means on the carrier being pivoted and the means on the lamp-house being fixed, said lamp house further provided with a colored transparent means for viewing the interior of the lamp house, and spring controlled means detachably clamped to the lamp house intermediate the ends thereof for shifting the lamp house and carrier to a position for photographically printing.

14. In a photographic printing machine a lamp house provided with means for suspending a lamp therein, a printing plate carrier abutting against the lower edge of the lamp house, said carrier and lamp house having coacting means for detachably clamping the carrier against the lower edge of the lamp house, said lamp house further provided with a colored transparent means for viewing the interior of the lamp house, spring controlled means detachably clamped to the lamp house intermediate the ends thereof for shifting the lamp house and carrier to a position for photographically printing, circuit connections for said lamp, and an adjustable circuit opening and closing device in said circuit and operated from the shifting means for the lamp house for controlling the period of activity of the lamp within the lamp house.

15. In a machine for photographically printing, a spring controlled intermittently shiftable, normally locked releasable carrier for shifting a sensitized surface to be printed upon, said carrier including a pair of bottom members, each formed with a vertical extension carrying guide rollers one of said bottom members arranged above the other, and a pair of track members, one arranged above the other, for the rollers carried by said bottom members.

16. In a machine for photographically printing, a spring controlled intermittently

shiftable, normally locked releasable carrier for shifting a sensitized surface to be printed upon, said carrier including a pair of bottom members, each formed with a vertical extension carrying guide rollers, one of said bottom members arranged above the other, a pair of track members, one arranged above the other, for the rollers carried by said bottom members, and a stop and escapement mechanism arranged below and providing means for intermittently releasing the carrier to permit of the intermittent shift thereof.

17. In a machine for photographically printing, a spring controlled intermittently shiftable, normally locked releasable carrier for shifting a sensitized surface to be printed upon, said carrier including a pair of bottom members, each formed with a vertical extension carrying guide rollers, one of said bottom members arranged above the other, a pair of track members, one arranged above the other, for the rollers carried by said bottom members, a stop and escapement mechanism arranged below and providing means for intermittently releasing the carrier to permit of the intermittent shift thereof, and means operated forwardly of the carrier for returning it to initial position.

18. In a photographic printing machine a lamp house provided with means for suspending a lamp therein, a printing plate carrier abutting against the lower edge of the lamp house, said carrier and lamp house having coacting means thereon for detachably clamping the carrier against the lower edge of the lamp house, the means on said lamp-house being fixed and the means on said carrier being pivoted, said lamp house further provided with a colored transparent means for viewing the interior of the lamp house, and a gage device coacting with the lamp house for initially setting the plate mounted in said carrier.

19. In a photographic printing machine a lamp house, a printing plate carrier detachably connected to the lower end of the lamp house, light excluding means associated with said carrier and lamp house, means for bodily shifting the lamp house and carrier in a direction towards a sensitized surface to be printed, a lamp suspended within said house, circuit connections for said lamp, an adjustable circuit opening and closing device in said circuit connection and operated from the shifting means for the lamp house for varying the period of activity of the lamp, and a gage device coacting with the lamp house for initially setting the plate mounted in said carrier.

20. A photographic printing machine comprising a carrier, a gravity movable sensitized body holder mounted on the carrier, means for shifting said carrier in one

- direction to position portions of the sensitized body on the holder to be successively photographically printed, a stop and escapement mechanism coacting with said carrier to provide for the intermittent shifting thereof a predetermined distance, means for photographically printing on said body after each shift of the carrier, a stop and escapement mechanism associated with said holder to provide for the intermittent shifting thereof in a direction at right angles to the shift of the carrier, said means including a printing plate, and a gage device associating with said means for initially setting said plate.
21. A photographic printing machine comprising means for shifting in one direction a sensitized body to position portions thereof to be photographically printed, a carrier for said means, means for intermittently releasing said carrier to permit of the latter shifting a predetermined distance in a direction at right angles to the direction in which said body was shifted to provide for aligning successive photographic prints in row-like form on said body, means shiftable towards said carrier for photographically printing said body after each shift of the carrier and including a light source and adjustable means for controlling the activity of said source and a printing plate, and a gage device associating with said last mentioned means for initially setting said plate.
22. In a photographic printing machine a lamp house provided with means for suspending a lamp therein, a printing plate carrier abutting against the lower edge of the lamp house, said carrier and lamp house having coacting means for detachably clamping the carrier against the lower edge of the lamp house, the means on the lamp-house being fixed and the means on said carrier being pivoted, said lamp house further provided with a colored transparent means for viewing the interior of the lamp house, spring controlled means detachably clamped to the lamp house intermediate the ends thereof for shifting the lamp house and carrier to a position for photographically printing, and a gage device associated with said lamp house for initially setting said printing plate.
23. A photographic printing machine comprising a transfer plate holder, a spring controlled intermittently shiftable carrier, said carrier and holder interengaging with each other to permit of the holder shifting on the carrier in a direction opposite to the travel of the carrier, a stop and escapement mechanism coacting with the holder to permit of the holder moving a predetermined distance in a direction at right angles to the direction of travel of the carrier, means including a stop and escapement mechanism to provide for the intermittent travel of the carrier, means shiftable towards the holder for photographically printing on the plate carried by the latter and including a light source, and a circuit opening and closing mechanism for said light source operated by said means for photographically printing.
24. A photographic printing machine comprising a transfer plate holder, a spring controlled intermittently shiftable carrier, said carrier and holder interengaging with each other to permit of the holder shifting on the carrier in a direction opposite to the travel of the carrier, a stop and escapement mechanism coacting with the holder to permit of the holder moving a predetermined distance in a direction at right angles of the direction of travel of the carrier, means including a stop and escapement mechanism to provide for the intermittent travel of the carrier, means shiftable towards the holder for photographically printing on the plate carried by the latter and including a light source, a circuit opening and closing mechanism for said light source operated by said means for photographically printing, said circuit opening and closing mechanism including means for varying the period of activity of the light source.

In testimony whereof, I affix my signature hereto.

ROBERT JARVIS SMOTHERS.
